US00D481782S

(12) **United States Design Patent**
Okazaki

(10) Patent No.: **US D481,782 S**
(45) Date of Patent: ** Nov. 4, 2003

(54) **HOLLOW FIBER MODULE FOR FILTRATION**

(75) Inventor: **Hiroyuki Okazaki**, Nagoya (JP)

(73) Assignee: **Mitsubishi Rayon Co., Ltd.**, Tokyo (JP)

(**) Term: **14 Years**

(21) Appl. No.: **29/166,169**

(22) Filed: **Aug. 23, 2002**

(30) **Foreign Application Priority Data**

Feb. 27, 2002 (JP) 2002-005048

(51) LOC (7) Cl. **23-01**

(52) U.S. Cl. **D23/209**

(58) Field of Search D23/207, 209;
210/321.8, 321.89, 323.2, 500.23

(57) **CLAIM**

The ornamental design for a hollow fiber module for filtration, as shown and described.

DESCRIPTION

FIG. 1 is a front perspective view of a hollow fiber module for filtration showing my new design;

FIG. 2 is a rear perspective view;

FIG. 3 is an enlarged left side elevational view;

FIG. 4 is an enlarged right side elevational view;

FIG. 5 is a top plan view, the bottom plan view being a mirror image of the top plan view;

FIG. 6 is a front elevational view, the rear elevational view being a mirror image of the front elevational view;

FIG. 7 is an enlarged view taken along line 7—7 in FIG. 6; and,

FIG. 8 is an enlarged view taken along line 8—8 in FIG. 6. The claimed design is shown fragmented in FIGS. 3 and 4 to indicate indeterminate length.
